TABLET ARM ACCESSORY

Erving B. Morgan, Grand Rapids, Mich., assignor to American Seating Company, Grand Rapids, Mich., a corporation of New Jersey

Application March 6, 1958, Serial No. 719,650

12 Claims. (Cl. 155—128)

The present invention relates to a tablet arm accessory for chairs, and particularly for folding chairs.

The primary objects of the invention are to provide a tablet arm accessory which can quickly be mounted on a chair and removed therefrom; to provide such an accessory which requires no fastening means such as clamps or bolts and nuts to mount it on a chair; to provide such a tablet arm accessory which is especially well adapted for use in conjunction with folding chairs and which is itself foldable when not in use so as to occupy a minimum of space for storage or shipping; and in general to provide such a tablet arm accessory for chairs which is simple and sturdy in construction, reasonably economical in manufacture, and attractive in appearance.

Illustrative embodiments of the invention are shown in the accompanying drawings, wherein:

Figure 1 is a side elevational view of a steel folding chair of the inverted-Y type with the new tablet arm accessory mounted thereon for use;

Figure 2 is a front elevational view of the same, the pivotally mounted tablet arm being shown in its use position in full lines, and in an upwardly swung non-use position in dotted lines;

Figure 3 is an enlarged, fragmentary, horizontal sectional view of parts of the same, taken on line 3—3 of Figure 1;

Figure 4 is a top plan view of the new accessory per se, in a folded non-use condition for storage or shipping;

Figure 5 is a side elevational view of the same;

Figure 6 is a side elevational view of a steel folding chair of the X type with a modified form of the invention mounted thereon for use;

Figure 7 is a fragmentary front elevational view of the same, the pivotally mounted tablet arm being shown in its use position in full lines, and in a downwardly swung non-use position in dotted lines;

Figure 8 is a bottom plan view of the modified form of the invention shown in Figures 6 and 7, the accessory being here shown in folded non-use condition;

Figure 9 is a side elevational view of the same;

Figure 10 is a side elevational view of another modification of the invention mounted on an X type steel folding chair;

Figure 11 is a side elevational view of still another modified form of the invention, the tablet arm accessory being here shown mounted on a X type wood folding chair; and

Figure 12 is a horizontal sectional view of parts of the same taken on line 12—12 of Figure 11.

Referring now in detail to these drawings, and referring first particularly to Figures 1—5, the tablet arm accessory there shown is particularly adapted for use in connection with a steel folding chair of the inverted-Y type, as shown. This chair comprises a tubular metal front frame bent to form the front legs 20 of the chair, tubular metal rear legs 21 pivotally connected at 22 to the front legs 20 above the seat level of the chair, and a chair seat 23 pivotally mounted on a rod 24 extending

2

between the front legs 20, the seat being also connected to the rear legs 21 by means of suitable links 25.

The tablet arm accessory comprises a frame generally designated 26 desirably fabricated from a length of metal tubing which is so bent that, when the accessory is mounted on the unfolded chair, it forms a forwardly-rearwardly extending upper part 27 in substantial parallelism with and above the chair seat, a forward arm 28 extending from the forward end of the upper part 27 rearwardly-downwardly alongside the chair legs 20, 21 at one side of the chair and below the seat level, and a rearward arm 29 extending from the rearward end of the upper part 27 rearwardly-downwardly alongside said legs 20, 21 above the seat level. The lower rearward ends of the arms 28, 29 are preferably flattened as shown.

A pair of channel brackets is secured to the rear portions of the frame's arms 28, 29 as by means of welding. The rear channel bracket 30 is secured top and bottom to the flattened rearwardmost ends of the arms 28, 29, while the front channel bracket is secured to said arms at an angle to the rear bracket equal to the downwardly divergent angle between the chair's front leg 20 and rear leg 21. The rear channel bracket 30 is cross-sectionally C-shaped and opens forwardly, while the front channel bracket 31 is cross-sectionally C-shaped and opens rearwardly, these brackets being thus adapted to snugly embrace the tubular legs of the chair.

The tablet arm 32 of the accessory is turnably mounted on the upper part 27 of the tubular frame 26 by means of strap bearings 33 secured to the underside of the tablet arm as by screws 34. The tablet arm is thus swingable between a lowered use position and a raised non-use position as seen in Figure 2. Releasable means are provided for supporting the tablet arm 32 in its lowered use position and as here shown this means comprises a brace 35 having its lower, outer end pivotally connected at 36 to the forward arm 28 of the frame 26 and having its upper, inner end slidably fitted into a slot 37 in an angle bracket 38 dependingly secured to the underside of the tablet arm. When the accessory is mounted on the chair, the tablet arm 32 can thus be swung upwardly to facilitate ingress to and egress from the chair, or it can be lowered to its use position, such lowering movement being limited by contact of the brace 35 with one end of slot 37. When the accessory is not in use the tablet arm 32 can be swung to its position of substantial alignment with the frame 26 as seen in Figures 4 and 5 so that the accessory assumes a flat condition for storage or shipping.

It will be seen that the accessory can be readily mounted on the unfolded chair by simply sliding its channel brackets 30, 31 downwardly over the chair's legs 20, 21, said brackets snugly but detachably embracing said legs to securely but removably hold the accessory in position on the chair. The accessory can be removed from the chair by simply lifting it off.

Figures 6—9 of the drawings show a modified form of the tablet arm accessory, applied to a steel folding chair of the X type. In this form of folding chair, the front legs 40 and rear legs 41 cross over and are pivotally connected to each other at 42 beneath the seat 43. As here shown the accessory is adapted for removable mounting on the upwardly diverging upper segments 44 and 45 of the front legs 40 and rear legs 41 respectively. In this form of the invention the frame 46 of the accessory comprises a length of metal tubing bent to form a forwardly-rearwardly extending upper part 47 in substantial parallelism with and above the chair seat, a forward arm 48 depending from the forward end of the upper part 47 and extending rearwardly alongside the segments 44, 45 of the chair legs, and a rearward arm

49 depending from the rearward end of said upper part 47 and extending forwardly alongside the leg segments 44, 45. A pair of channel brackets 50, 51 are welded to the frame's arms 48, 49 and are disposed at the same upwardly divergent angle as the upper leg segments 44, 45, being thus adapted to detachably embrace said leg segments 44, 45 for removably mounting the accessory on the chair. In this form of invention the tablet arm 52 is turnably mounted by strap bearings 53 on the frame's upper part 47 so as to swing downwardly from its use position to a folded, non-use position for storage as seen in Figures 8 and 9. In its use position, seen in Figures 6 and 7, the tablet arm 52 is supported by a brace 55 pivotally connected at 56 to the frame's forward arm 48 and engageable in a notch 57 in an angle bracket 58 secured to the underside of the tablet arm 52. The accessory as here shown is mounted on and removed from the chair in a manner similar to that described in connection with the form of the invention shown in Figures 1-5.

The species of the invention shown in Figure 10 is the same as that shown in Figures 6-9 except that in this form of the invention the frame's rearward arm 59 is extended and bent as shown to provide a mounting for an additional pair of channel brackets 60, 61 which engage the downwardly diverging lower segments 62, 63 of the chair's legs.

Figures 11 and 12 show a modification of the invention which is specially adapted for use with an X type wood folding chair having cross-sectionally rectangular legs. In this modification the tubular frame's forward arm 80 and rearward arm 81 depend from its upper part 82 and extend rearwardly alongside the lower segments 83, 84 of the chair's legs. The channel brackets 85, 86 secured to the arms 80, 81 are right angularly formed so as to snugly engage the chair's legs when the accessory is mounted on the chair.

Although the invention is primarily intended for use with, and herein shown and described in connection with folding chairs, it can also be well adapted for use with chairs of the fixed type and, in fact, with chairs of any type wherein the chair legs have either downwardly divergent or upwardly divergent segments. And while but several specific embodiments of the invention have been herein shown and described it will be understood that numerous other embodiments might be conceived without departing from the spirit of the invention or the scope of the following claims.

I claim:

1. A tablet arm accessory for an inverted-Y type folding chair having forwardly-downwardly extending front legs and rearwardly-downwardly extending rear legs hingedly connected at their upper ends to the front legs above the level of the chair seat, said accessory being adapted for removable mounting on the downwardly diverging pair of front and rear legs at one side of the unfolded chair, and said accessory comprising: A frame fabricated from a length of metal tubing bent to form a forwardly-rearwardly extending upper part in substantial parallelism with and above the chair seat, a forward arm extending from the forward end of said upper part rearwardly-downwardly alongside said pair of legs below the level of the chair seat, and a rearward arm extending from the rearward end of said upper part rearwardly-downwardly alongside said pair of legs above the level of the chair seat; a pair of elongated channel brackets mounted on the lower rearward end portions of said arms and adapted to detachably embrace said front and rear legs respectively for removably mounting the accessory on the chair, said brackets being clamped downwardly by the weight of the accessory into snug engagement with the chair legs respectively and being of sufficient length to positively locate said accessory and removably support the accessory on the chair with no

other means of attachment; and a tablet arm mounted on the upper part of said frame.

2. A tablet arm accessory according to claim 1 in which said pair of channel brackets comprises a rear channel bracket secured to the rearward ends of said forward and rearward arms, said rear bracket opening forwardly so as to nest around the rearward surfaces of said rear chair leg; and a front channel bracket secured to said forward and rearward arms at an angle to the rear bracket equal to the downwardly divergent angle between said pair of chair legs, said front bracket opening rearwardly so as to nest around the forward surfaces of said front chair leg.

3. A tablet arm accessory for an X type folding chair having pairs of legs pivotally connected together beneath the chair seat, said accessory being adapted for removable mounting on the upwardly diverging upper segments of the crossed-over pair of chair legs beneath the chair seat and at one side of the unfolded chair, and said accessory comprising: a frame fabricated from a length of metal tubing bent to form a forwardly-rearwardly extending upper part in substantial parallelism with and above the chair seat, a forward arm depending from the forward end of said upper part and extending alongside said upwardly diverging upper leg segments, and a rearward arm depending from the rearward end of said upper part and extending alongside said upwardly diverging upper leg segments; a pair of elongated channel brackets secured to the portions of said arms extending alongside said upper leg segments, said brackets being disposed at the same upwardly divergent angle as said upper leg segments and being adapted to detachably embrace said upper leg segments for removably mounting the accessory on the chair, said brackets being clamped downwardly by the weight of the accessory into snug engagement with the chair legs respectively and being of sufficient length to positively locate said accessory and removably support the accessory on the chair with no other means of attachment; and a tablet arm mounted on the upper part of said frame.

4. A tablet arm accessory for an X type folding chair having pairs of legs pivotally connected together beneath the chair seat, said accessory being adapted for removable mounting on the downwardly diverging lower segments of the crossed-over pair of chair legs beneath the chair seat and at one side of the unfolded chair, and said accessory comprising: a frame fabricated from a length of metal tubing bent to form a forwardly-rearwardly extending upper part in substantial parallelism with and above the chair seat, a forward arm depending from the forward end of said upper part and extending alongside said downwardly diverging lower leg segments, and a rearward arm depending from the rearward end of said upper part and extending alongside said downwardly diverging lower leg segments; a pair of elongated channel brackets secured to the portions of said arms extending alongside said lower leg segments, said brackets being disposed at the same downwardly divergent angle as said lower leg segments and being adapted to detachably embrace said lower leg segments for removably mounting the accessory on the chair, said brackets being clamped downwardly by the weight of the accessory into snug engagement with the chair legs respectively and being of sufficient length to positively locate said accessory and removably support the accessory on the chair with no other means of attachment; and a tablet arm mounted on the upper part of said frame.

5. A tablet arm accessory for an X type folding chair having pairs of legs pivotally connected together beneath the chair seat, said accessory being adapted for removable mounting on the upwardly diverging upper segments and the downwardly diverging lower segments of the crossed-over pair of chair legs beneath the chair seat and at one side of the unfolded chair, and said ac-

cessory comprising: a frame fabricated from a length of metal tubing bent to form a forwardly-rearwardly extending upper part in substantial parallelism with and above the chair seat, a forward arm depending from the forward end of said upper part and extending alongside said crossed-over pair of chair legs, and a rearward arm depending from the rearward end of said upper part and extending alongside said crossed-over pair of chair legs; an upper pair of channel brackets and a lower pair of channel brackets secured to the portions of said arms extending alongside said crossed-over pair of chair legs, the upper pair of brackets being disposed at the same upwardly divergent angle as said upper leg segments and being adapted to detachably embrace said upper leg segments, and the lower pair of brackets being disposed at the same downwardly divergent angle as said lower leg segments and being adapted to detachably embrace said lower leg segments, all for removably mounting the accessory on the chair; and a tablet arm mounted on the upper part of said frame.

6. A detachable tablet arm accessory for a chair having at one side thereof divergent front and rear legs, said accessory comprising: a frame adapted for disposition along said one side of the chair and extending above the chair seat; a tablet arm mounted on the upper part of said frame; and a pair of elongated brackets mounted on the lower part of said frame in divergent disposition conforming to the divergence of said front and rear legs, the front bracket being detachably engageable with the front chair leg and the rear bracket being detachably engageable with the rear chair leg, said brackets being clamped downwardly by the weight of the accessory into snug engagement with the chair legs respectively and being of sufficient length to positively locate said accessory and removably support the accessory on the chair with no other means of attachment.

7. A detachable tablet arm accessory according to claim 6 in which the front and rear legs, and the front and rear brackets, are downwardly divergent.

8. A detachable tablet arm accessory according to claim 7 in which the front bracket is of rearwardly opening form so as to nest with the front surface of the front chair leg and the rear bracket is of forwardly opening

form so as to nest with the rear surface of the rear chair leg.

9. A detachable tablet arm accessory according to claim 7 in which the front bracket is of rearwardly opening channel form so as to nest with the front surface of the front chair leg and the rear bracket is of forwardly opening channel form so as to nest with the rear surface of the rear chair leg.

10. A detachable tablet arm accessory according to claim 6 in which the front and rear legs are fabricated of metal tubing and in which the front and rear brackets are of cross-sectionally C-shaped channel form so as to snugly nest with said chair legs.

11. A detachable tablet arm accessory according to claim 6 in which said frame comprises a length of metal tubing bent to form a forwardly extending upper part in substantial parallelism with the chair seat on which upper part said tablet arm is mounted, and depending forward and rearward arms on the lower parts of which said brackets are mounted.

12. A detachable tablet arm accessory according to claim 11 in which the tablet arm is turnably mounted on the upper part of the tubular frame for swinging movement between a non-use vertical position and a use position overhanging the chair seat, and releasable means for supporting the tablet arm in said use position.
